APPARATUS AND METHOD FOR SPRAY
DRYING AND COOLING

Gerald D. Arnold, Wauwatosa, Wis.

Application July 29, 1943, Serial No. 496,574

15 Claims. (Cl. 159—4)

1
This invention relates to improvements in apparatus and methods for spray-drying and cooling.

It is the primary object of the invention to provide novel and improved means for spray drying and, particularly, to associate such means with means for immediately cooling the dried product. It is my purpose to dry the material in a pneumatic convection current of dry hot gas and to separate the dried product from the drying gases in the same chamber and the same vortex in which drying is effected.

It is a further object of the invention to provide a method of drying and cooling whereby the cooling may be effected in a continuously recirculated stream of fluid refrigerant which is re-cooled in such circuit, the dehydration of the product precluding the dust-like product from adhering to the cooling coils.

Other objects of the invention will be made apparent to those skilled in the art upon analysis of the following disclosure.

In the drawings:

Fig. 1 is a view partially in side elevation and partially in vertical section diagrammatically illustrating a drying and cooling unit embodying the invention.

Fig. 2 is a view taken in section on line 2—2 of Fig. 1.

Fig. 3 is a view taken in section on the line 3—3 of Fig. 1.

Fig. 4 is an enlargement detail fragmentarily illustrating this position of the spray nozzle used in the dehydrating section of the apparatus.

Fig. 5 is an enlarged detail showing in section a portion of cooling coils used in the cooling section of the apparatus.

Fig. 6 is a fragmentary detail of a modified conveyor arrangement illustrated partly in section and partly in side elevation.

Like parts are designated by the same reference characters throughout the several views.

The drying and separating chamber 7 has a volute air inlet at 8 for the drying gas. Such gas is usually heated before its admission and the pipe 8 may therefore be understood to communicate with a heater or furnace (not shown).

As the arc of the inlet 8 approaches the cylindrical upper wall 9 of the drying chamber, it is also inclined helically downwardly, its downward pitch being approximately equal in one revolution to its thickness so that the air current delivered to the chamber 7 will tend to pass in one revolution beneath the current of gas newly admitted. This minimizes eddies in the chamber.

2
Below the cylindrical portion 9 of the separating and drying chamber, there is a frusto-conical section 10 leading to a delivery section 11 which has a helically pitched undercut shoulder at 12 which acts like a screw upon the rotating solids to advance them axially of the chamber toward its discharge port 14.

The chamber is provided at 15 with a discharge sleeve for the gases. This communicates by means of boot 16 with the inlet to a blower casting 17. The tangential outlet 18 from the blower is preferably arranged to permit the runner of the blower to rotate in a direction opposite to that in which the gases and dried material rotate in the vortex formed in the separator 7. Assuming the vortex in the drying and separating chamber to rotate counterclockwise as viewed in Fig. 2 the disposition of the tangential outlet 18 will be such that the rotation of gases in the blower chamber 17 will be clockwise. This construction is preferred for reasons of sanitation, since thereby all baffles on which material might accumulate are omitted. However, it is not essential to the invention. When this feature is used, it will be understood that the vortex in the cyclone may be in either direction as long as the vortex in the fan is opposite.

Surrounding the discharge sleeve 15 for the gases is a wall 19 providing an annular well at 20 for a set of spray apertures 23 opposite the respective nozzles 21. The pipes 22 leading to the several nozzles may be connected by a header 24 supplied with the material to be dried through pipe 25 from a high pressure pump such as gear pump 26. Such material is usually pre-heated and concentrated and strained, but the inventor is not concerned with this preliminary treatment. The annular well at 20 in which the several nozzles are disposed is open at its top to permit the nozzles and their associated header to be lifted as a unit for cleaning or inspection of the nozzles. It preferably, however, is provided with a cover 200 tightly fitted about pipes 22 to prevent atmospheric air from reaching the chamber 7 through the well 20 and apertures 23.

The nozzles and the respective apertures 23 through which their spray is directed are preferably arranged upon a helical path corresponding in pitch to the helical path followed by the current of gases admitted through the conduit 8 to the drying and separating chamber. The stream of drying gas is held centrifugally to the cylindrical wall portion 9 of the chamber 7 in the path of the spray discharged from the several nozzles 21 so that none of the atomized ma-

terial to be dried can reach the casing wall, all of it being entrained in the convection current of drying gases.

Ordinary drying will be effected instantaneously upon contact of the atomized spray with the drying gas. Thereupon the resulting dry powder will continue to move with the convection current of gas but will be separated centrifugally therefrom so that when the dried powder reaches the undercut shoulder 12 it will be forcibly expelled from the separator while the gas, turning at this point to escape through outlet sleeve 15, will be substantially free of the dried material.

To minimize the velocity of the air at the point where it leaves the separating chamber, thereby minimizing the amount of dried product which will be carried out of the chamber with the air, I employ the principle of rotating the gases in the fan casing in a direction which is reverse to their direction of rotation in the separating chamber, as above explained. I have found that the clockwise vortex in the fan chamber will be communicated downwardly from the fan casing inlet until it interacts with the counterclockwise vortex in the separating chamber. At this point of interaction, which will usually occur immediately below the flared inlet 27 to the discharge sleeve 15, the rotative velocity of the gases will be substantially eliminated and the gases will have only a vertical or axial velocity which will not normally be enough to lift dust from the separator.

However, inasmuch as spray-dried material is frequently of considerable value, I prefer to employ a second stage of separation for removing from the drying gases the last vestige of dust. The separator 30 in which the second stage separation occurs receives tangentially the discharge from blower 17. It has a discharge sleeve at 31 which may open at 32 to outer air. Around the sleeve 31 is a sleeve 33 which may recirculate some of the gases and dust in the manner disclosed in my Patent Ser. No. 466,576, filed November 23, 1942, now abandoned entitled Centrifugal Separators.

The solids are delivered through discharge end 34 of the secondary separator in the manner already described and, through pipe 35, they reach a conveyor tube 36 into which the first separator also discharges.

A screw conveyor comprising three sections 37, 38 and 39 operates in tube 36. The sections are continuous, each with the other, save where interrupted by transverse baffles 40 and 41 which close approximately the upper half of the conveyor tube 36 between the respective conveyor sections. When the material dehydrated is being supplied from the separators in sufficient quantity to substantially fill the tube 36, such material will be passed virtually without interruption from one conveyor section to another. However, when the material is inadequate to fill the tube, then the gap between conveyor sections will tend to allow a certain residuum of material to remain between sections where it will cooperate with the baffle to form a seal precluding any transfer of air or other gas from one section to the other. The purpose of this arrangement is to insure the sealing of the conveyor tube to preclude the mixing of the hot, humid air used for dehydration with the chilled gas later used for cooling the material.

All of the material, whether derived from the dehydrator-separator 7 or the secondary separator 30, passes through the conveyor tube 36

into pipe 43 which is in a closed refrigeration circuit which includes cooler separator 45, fan casing 46, and refrigerator casing 47. The cooler separator 45 is preferably substantially identical with the separator shown at 30. The cooling gas set in motion in the fan casing 46 circulates through the closed system with sufficient velocity to entrain the material delivered into pipe 43 and to project such material tangentially into cooler separator 45 with sufficient velocity for the centrifugal separation of the solids from the gas. The solids are discharged through the rotary valve at 48 into a barrel or other container 49 while the gases pass upwardly through the gas return pipe 50 to the eye of the fan casing 46. Since the gases rotate counterclockwise in cooler separator 45, the fan casing 46 is preferably arranged for clockwise circulation so that the vortex communicated downwardly from the fan into the separator will oppose and tend to neutralize at some point within the separator the vortex established therein, thus minimizing the amount of material which will be carried upwardly from cooler separator 45 with the gases. However, this is relatively immaterial in the cooling section of the device for the reason that the closed circuit for refrigerating gases precludes any loss of material provided the material has been dehydrated sufficiently and provided further that the cooling coils 55 in the chamber 47 have sufficient area and operate at such temperatures as not to cool the refrigerating gases below the dew point.

Under such conditions the dust-like material carried with the circulating gases from the cooler separator 45 and passing through the fan casing 46 will not adhere to the coils 55 but will pass through such coils with the gaseous current and be returned to the separator and commingled with the material newly arriving through conveyor tube 36.

The coils themselves will preferably be designed in such a way as to minimize any tendency for adherence of dust thereto. The refrigerant supplied from compressor 56 through radiator 57 preferably passes through pipes 58 (Fig. 5) which are arranged in banks or tiers, the several runs of pipe in each tier being enclosed in a common envelope 60 which has smooth wall surfaces joined above and below the tier of pipes to form smooth walled passages at 61 through which the gaseous coolant and any entrained dust will pass virtually unimpeded. The sheaths 60 not only serve to protect the pipes themselves from dust accumulation, but they also provide extended heat absorption surfaces for the coils.

If desired, banks of fin coils may be substituted as disclosed in my companion application entitled "Closed Hammer Mill Circuits," executed of even date herewith and now Patent No. 2,400,382.

If, notwithstanding the tendency of the circulating gas to scour the surfaces 60, should any dust accumulate thereon, these surfaces may readily be cleaned by merely opening the door 62 with which the cooling chamber 47 is provided.

Dehydration of the material acted upon in the apparatus should preferably be carried to such an extent as to reduce the moisture content of the material below 10%, and preferably as low as 6%, to avoid raising the humidity of the cooling gas circulating in the cooling section of the apparatus. The gas circulated for cooling purposes should not be cooled below 32 to 38 degrees F., and should be circulated in sufficient

quantity so that the return gas reaching the cooling chamber 47 from the fan should preferably be about 60 degrees. Cooling below 60 degrees F. is not only expensive but tends to cause condensation on the material, undesirably dampening it. Under these conditions the dehydration of the material to the specified moisture content will keep both the material and the dehydrating gas dry even while passing over the refrigerating coils.

Although it is necessary to discharge to the atmosphere the hot humid air used for dehydration, the auxiliary separator of the type disclosed will preclude any substantial loss of the dehydrated material at this point and the operation of the system in accordance with the method above described will prevent the loss of any material whatever in the cooling section. The organization disclosed has the further advantage that it is not only efficient and economical of material, but it is compact and relatively inexpensive and delivers a high quality of material which would be impossible to achieve but for the immediate cooling following dehydration.

Particularly where the material is a food product it is desirable for the purpose of promoting sanitation, as well as preventing possible fire loss, to incorporate in each of the several separators an obliquely disposed partition or wall such as that shown at 65 in the dehydrator-separator 7 in Fig. 1. This oblique wall 65 spans the angle between the wall 19 and the top 9' of the dehydrator separator to exclude the material from what would otherwise constitute dead space in which dust collects and cakes in the ordinary separator. The wall 65 should extend far enough to be secured by the current of newly admitted gases to prevent any accumulations thereon.

For many installations it may be desirable for the dryer cyclone 7 and the auxiliary cyclone 30 to discharge directly into the return conveyor circuit which handles the refrigerating gases. Fig. 6 suggests a possible arrangement of this sort.

The lower end 14 of cyclone 7 and the pipe 35 from the bottom of cyclone 30, are both shown in Fig. 6 provided with rotary valves 68, 69, operated at a rate to pass all solids but no substantial amount of dehydrating gases. These valves discharge directly into conduit 430 which leads from the cooling chamber 47 to the cooler separator cyclone 45. Thus the screw conveyor is dispensed with and pneumatic convection is substituted, while the humid gases from separators 7 and 30 are still excluded from the refrigerating gas of the closed circuit which includes cooler separator 45.

While my apparatus and method have been described in detail it may be appropriate to note by way of summary that the drying of the material to the predetermined point mentioned permits the cooling thereof in a closed circuit so that in the entire apparatus there is only one point at which powdered material can possibly escape, that being in the course of the necessary discharge of the saturated drying gases. Both the drying section and the cooling section accomplish a plurality of functions in the respective vortices. In a single vortex in the chamber 7 the material to be dehydrated is dried by the gaseous current in which it is pneumatically conveyed and is concurrently separated centrifugally from such current. In the vortex of the cooling section the material is not only cooled by the gaseous current by which it is

conveyed, but is simultaneously centrifugally separated from the gas of such current.

In the drying section dehydration is facilitated by the fact that the blower fan used to establish the vortex maintains the chamber 7 under subatmospheric pressure which reaches a minimum in the central portion of the vortex into which the material to be dehydrated is released by the atomizing nozzles 21. Under such subatmospheric conditions as exist in the central portion of the vortex and in a chamber maintained under subatmospheric pressure by the exhaust fan, dehydration of the atomized material is normally instantaneous.

If, in dealing with certain material, it is desirable to provide a stream of air about the atomizing nozzle to partially relieve the vacuum or to entrain the atomized product, it is only necessary to omit or remove or open the cover 200 for well 20, whereupon air will be admitted through the well to enter the chamber 7 through the apertures 23, along with the atomized spray.

I claim:

1. A dehydrator-separator comprising the combination with a chamber wall of circular cross section provided with a tangential inlet for dehydrating gas, of a gas discharge sleeve centrally located in said chamber and about which a current of dehydrating gas flows in a vortex, means for establishing a pressure differential to induce the creation of a vortex of dehydrating gas, an atomizing nozzle for material to be dehydrated, said nozzle being positioned outwardly radially of said sleeve and directed outwardly toward said chamber wall for delivering atomized material into the vortex of dehydrating gas, said tangential inlet being of substantial radial extent to deliver a moving column of dehydrating gas across the nozzle in a direction transverse to the axis of the vortex, means disposed outside said sleeve for supplying such material to said nozzle under pressure to be atomized by the nozzle, and mechanical means for effecting and controlling the discharge of dehydrated material from the bottom of the chamber, the vortex current of dehydrating gas in said chamber being adapted to effect both the dehydration of the atomized material and the separation of the dehydrated product centrifugally from the current.

2. A drying and separating chamber including a casing of generally circular form having a lower portion tapered to a reduced diameter and provided with an outlet for solids, said casing being provided with a tangential inlet and a centrally disposed outlet sleeve for gases, a wall spaced outside of said sleeve and connected thereto within the casing and forming an annular well between the sleeve and wall, an atomizing nozzle disposed in said well and provided with supply connections for material to be dehydrated, said nozzle being directed outwardly toward said casing into the path of gas admitted thereto from said inlet, and the wall having an aperture for passing the atomized material from the nozzle to the interior of the casing.

3. A device of the character described comprising a drying and separating chamber including a casing with a tangential inlet and a centrally disposed gas outlet sleeve, a wall about said sleeve in spaced relation thereto, the annular space between the wall and sleeve constituting a well, means providing a connection between the wall and sleeve within the casing at the bottom of the well, the wall being provided with

spaced apertures affording communication between the well and the casing, a set of atomizing nozzles within the well registering with the respective apertures for discharging a spray of atomized material through the apertures into the casing, a header provided with connections to the several nozzles for supplying material thereto, said header and nozzles being unitarily movable axially with respect to the casing for withdrawing the nozzles from the well.

4. A drying and separating chamber comprising in combination a chamber casing provided with a tangential inlet and a centrally disposed outlet sleeve, a fan and fan casing having an inlet communicating with said sleeve for withdrawing air from said casing and drawing air into the tangential inlet of said casing to establish a vortex current therein, a wall about the sleeve and connected thereto within the casing, said wall being spaced from the sleeve to constitute therewith an annular well about the sleeve, and an atomizing nozzle disposed in said well and adapted to be withdrawn upwardly therefrom, said nozzle being directed outwardly of said wall into the path of the vortex current of dehydrating gas in the casing, and the wall having an aperture registering with the nozzle for admitting the spray of the nozzle to the said current.

5. The device of claim 4 in which the inlet of the fan casing is axially aligned with the sleeve and the blower fan casing has a tangential outlet providing for vortex rotation in said fan casing in a direction opposite to the direction of vortex rotation in the separator casing.

6. The device of claim 4 in which the chamber casing is provided about said sleeve and wall with an obliquely disposed false wall extending to the top of the casing and constituting means for excluding dust from the top inner portion of the casing closest to the gas outlet sleeve.

7. A drying and separating chamber comprising the combination with a chamber casing having a tangential inlet and a central outlet casing within the chamber and an end wall closing said chamber casing outside of said outlet casing, of an obliquely disposed partition wall within said chamber casing, extending about the outlet casing and connecting the outlet casing with the end wall of the casing whereby to exclude from the angle between the end wall and the outlet casing dust which might otherwise accumulate therein.

8. In drying apparatus the combination with a pair of cyclone separators having gas inlets and outlets, of means for passing dehydrating gas and entrained material from the outlet of one of said separators to the inlet of the other, each of said separators having a discharge outlet for solids, and a conveyor system including a conduit communicating with the aforesaid outlets for solids of the respective separators for receiving material from both separators, said conveyor comprising a plurality of separate screw sections in said conduit, and said conduit having partition means extending transversely of its upper portion between conveyor sections whereby to establish a seal in said conduit, said partition means terminating in spaced relation to the lower portion of the conduit whereby to leave a passage for solids.

9. Drying and cooling apparatus comprising a centrifugal dehydrator-separator provided with a tangential gas inlet, a central gas outlet and gas circulating means for establishing gas flow

into the inlet and out of the outlet for inducing a vortex of dehydrating gas within the dehydrator-separator between the inlet and outlet, a nozzle arranged to discharge material for dehydration into the vortex within the dehydrator-separator, said dehydrator-separator having a discharge port for material dehydrated and separated in the vortex, a refrigerating separator having a closed recirculating gaseous circuit exclusive of said dehydrator-separator and including a circulating blower, means for delivering the separated dehydrated material from said discharge port into said closed recirculating gaseous circuit while substantially precluding communication of the recirculating gas in the closed circuit with the dehydrating gas, and means for chilling the dehydrated material including a refrigerator exposed in said closed circuit to gas circulated therein by said blower, a connection from the dehydrator-separator material-discharge port into said recirculating gaseous circuit for delivering into the closed circuit of the refrigerating separator solids received from the discharge port of the dehydrator-separator for the cooling of said solids in gas circulating in the closed circuit of the refrigerating separator and the centrifugal discharge of the cool solids from such last mentioned gas in the refrigerating separator, and means controlling the discharge of solids from the refrigerating separator.

10. In a dehydrator the combination with a pair of cyclone separators having gas inlets and outlets and means for passing dehydrating gas and entrained material from the outlet of one of said separators to the inlet of the other, each of said separators having a discharge outlet for solids, and a closed conveyor system exclusive of said separators and including a tube communicating with the aforesaid solids outlets of the respective separators for receiving material from both separators, said system comprising a closed pneumatic conveyor means incorporating said conveyor tube and the respective separator solids outlets but isolated from the means for conveying gas and entrained material between separators, and rotary means for passing solids to said tube, while excluding gases from passing from the separators to the conveyor means.

11. A method of dehydration which includes the establishment of a vortex of dehydrating gas and the spraying of atomized material from within the vortex outwardly into the vortex to be conveyed and dehydrated by the gas of the vortex and separated centrifugally from the vortex by the energy thereof, the segregation of the dehydrating gas from the solids separated therefrom while changing the direction of rotation of the segregated gas and the substantially continuous discharge of both the gas and the separated solids from the vortex.

12. The method of dehydration recited in claim 10 in combination with the further method steps, of delivering such solids substantially free of dehydrating gas into a closed circuit of circulating cooling gas, establishing a recirculating flow of cooling gas in the closed circuit, establishing a vortex of cooling gas in the closed circuit, and entraining the dehydrated solids in the cooling gas of said vortex to be simultaneously cooled thereby and centrifugally expelled from said vortex, and finally withdrawing the expelled cooled and dehydrated solids from the last-mentioned vortex.

13. The method of cooling which involves the

establishment of a current of cooling gas in a closed circuit, establishing a vortex of cooling gas in said closed circuit, delivering finely divided dehydrated material into said cooling gas to be entrained thereby for movement with said gas through said vortex and the discharge of such material independently of the gas from the vortex, substantially all of the cooling of the material, as well as its separation from the gas, being effected in said vortex.

14. In a combination dehydrator-separator and cooler, in which the material to be dehydrated is introduced into a vortex of dehydrating gas wherein it is simultaneously dehydrated and separated from such gas, the combination with closed circuit connections and a cooling gas there-in of means for introducing the resulting dehydrated solid directly into the path of said cooling gas to be entrained thereby, a circulating blower for establishing a high velocity current 20 of said cooling gas through such connections, a refrigerator in the path of the circulating cooling gas for abstracting heat therefrom in the course of its circulation, and a centrifugal separating chamber included in said connections 25 and having a tangential inlet and an axial outlet for said cooling gas and a separate axial outlet for removing the dehydrated cooled solid, said blower maintaining a sufficient velocity of said cooling gas to effect separation of the cooled solid 30 from said cooling gas centrifugally in the said chamber while such solid is being cooled by exposure to the refrigerated gas, said separating chamber having means controlling the discharge of solids therefrom independently of said cooling 35 gas in said closed circuit.

15. In a method of dehydrating and cooling, in which dehydration is effected in a gaseous vortex at sufficient velocity to separate the dehydrated material from the dehydrating gas, 40 the steps which comprise establishing cooling gas flow in a closed circuit in a current with sufficient velocity to entrain the dehydrated solids, in-

troducing said dehydrated solids into said circuit independently of said dehydrating gas to be entrained in the cooling gas current in such circuit, establishing in said circuit a vortex of said cooling gas and entrained solids in which the solids are simultaneously cooled and centrifugally discharged from said current, separating the cooling gas from the solids, refrigerating the cooling gas, whereby to extract from the cooling gas heat derived from the solids previously cooled, and expelling the cooled and dehydrated solids substantially free of the recirculating gas, the recirculating gas being confined in said closed circuit out of contact with said dehydrating gas whereby to avoid condensation of moisture in the latter.
